CLAIM

The ornamental design for a combined container and lid, as shown and described.

DESCRIPTION

FIG. 1 is a top, front, right isometric view of a combined container and lid, showing my new design;

FIG. 2 is a bottom, rear isometric thereof;

FIG. 3 is a top, rear isometric view thereof;

FIG. 4 is a front elevation view thereof;

FIG. 5 is a rear elevation view thereof;
FIG. 6 is a left side elevation view thereof;
FIG. 7 is a right side elevation view thereof;
FIG. 8 is a top plan view thereof;
FIG. 9 is a bottom plan view thereof;
FIG. 10 is a top, rear isometric view thereof, in a condition of use;
FIG. 11 is another top, rear isometric view thereof, in another condition of use;
FIG. 12 is a top, front, right isometric view of the lid of the combined container and lid;
FIG. 13 is a bottom, rear isometric view thereof;
FIG. 14 is a top, rear isometric view thereof;
FIG. 15 is a front elevation view thereof;
FIG. 16 is a rear elevation view thereof;
FIG. 17 is a left side elevation view thereof;
FIG. 18 is a right side elevation view thereof;
FIG. 19 is a top plan view thereof;
FIG. 20 is a bottom plan view thereof;
FIG. 21 is a top, rear isometric view thereof, in a condition of use;
FIG. 22 is a top, front, right isometric view of the container of the combined container and lid;
FIG. 23 is a bottom, rear isometric view thereof;
FIG. 24 is a top, rear isometric view thereof;
FIG. 25 is a front elevation view thereof;
FIG. 26 is a rear elevation view thereof;
FIG. 27 is a left side elevation view thereof;
FIG. 28 is a right side elevation view thereof;
FIG. 29 is a top plan view thereof; and,
FIG. 30 is a bottom plan view thereof.

The broken lines shown in FIGS. 2, 9, 11-18, 20, 21, 22-24, 29 and 30 depict portions of the combined container and lid that form no part of the claimed design. The broken lines shown in FIG. 10 is for environmental structure only and form no part of the claimed design.
